US0D1012696S

(12) **United States Design Patent** (10) Patent No.: **US D1,012,696 S**
(45) Date of Patent: ** Jan. 30, 2024

(54) **CLOSURE FOR CONTAINER**

(71) Applicant: **TOPPAN INC.**, Tokyo (JP)

(72) Inventors: **Takeshi Saito**, Tokyo (JP); **Satoshi Iwata**, Tokyo (JP)

(**) Term: **15 Years**

(21) Appl. No.: **35/515,331**

(22) Filed: **Aug. 25, 2022**

(80) **Hague Agreement Data**

Int. Filing Date: **Aug. 25, 2022**

Int. Reg. No.: **DM/223707**

Int. Reg. Date: **Aug. 25, 2022**

Int. Reg. Pub. Date: **Oct. 7, 2022**

(30) **Foreign Application Priority Data**

Feb. 28, 2022 (JP) ..... 2022-004021 D

(51) **LOC (14) Cl.** **09-07**

(52) **U.S. Cl.**

USPC **D9/439**

(58) **Field of Classification Search**

USPC ..... D9/434, 435, 445, 439, 452; D7/387, D7/391, 392.1, 396.1, 396.2, 396.6, 601, (Continued)

(57) **CLAIM**

The ornamental design for a closure for container, as shown and described.

DESCRIPTION

1. Closure for container
2. Closure for container
3. Closure for container
4. Closure for container
- 1.1 : Perspective
- 1.2 : Perspective
- 1.3 : Front
- 1.4 : Top
- 1.5 : Bottom
- 1.6 : Left
- 1.7 : Reference perspective view of parts
- 1.8 : Reference perspective view of parts
- 1.9 : Reference perspective view of parts
- 1.10 : Cross sectional
- 1.11 : Reference cross-sectional view of parts
- 2.1 : Perspective
- 2.2 : Perspective
- 2.3 : Front
- 2.4 : Top
- 2.5 : Bottom
- 2.6 : Left
- 2.7 : Reference perspective view of parts
- 2.8 : Reference perspective view of parts
- 2.9 : Reference perspective view of parts
- 2.10 : Cross sectional
- 2.11 : Reference cross-sectional view of parts
- 3.1 : Perspective
- 3.2 : Perspective
- 3.3 : Front
- 3.4 : Top
- 3.5 : Bottom
- 3.6 : Left
- 3.7 : Reference perspective view of parts
- 3.8 : Reference perspective view of parts
- 3.9 : Reference perspective view of parts
- 3.10 : Cross sectional
- 3.11 : Reference perspective view of parts
- 4.1 : Perspective
